UNITED STATES PATENT OFFICE.

TANOUS H. DAVID, OF SACRAMENTO, CALIFORNIA.

WHEELED MASSAGING DEVICE.

Application filed May 10, 1926. Serial No. 108,128.

This invention relates to chiropractic massaging devices and to one which is adapted to be used by the patient in his home to treat the spinal column.

5 A particular object of the invention is to provide a massaging device which can be made of a minimum number of parts and which can be readily adapted for use by the patient in his home for the purposes of 10 massaging the spine.

The deformities of the spine which are corrected by chiropractic treatments, are caused by the segmental vertebra sections becoming slightly disarranged, that is, one of 15 the sections of the vertebra will get out of alignment due to some mishap to the spinal column, with the result that the patient suffers various nervous disorders and diseases and in order to correct these conditions and 20 to put the vertebra sections back into alignment, massage is necessary. Adjustment of the spinal column, is also necessary in this treatment but this invention is directed particularly to an apparatus or device for massage purposes and a particular object of the 25 invention is to provide a massaging device which can be adjusted in width to suit the various spinal columns to which it may be applied so that the proper portion of the 30 spinal column may be massaged with beneficial results.

In order to enable others skilled in the art to fully comprehend the underlying features of my invention that they may embody the same in the various modifications 35 in structure and relation contemplated, a drawing depicting a preferred form has been annexed as a part of this disclosure and in such drawing, similar reference characters 40 denote corresponding parts throughout all the views, of which,

Figure 1 is a view in side elevation of a massaging device.

Figure 2 is a view in end elevation of the 45 massaging device illustrated in Figure 1.

Figure 3 is a view in side elevation of a modified form of massaging device having an adjustable feature connected therewith, the device being formed from a single piece 50 body portion.

Figure 4 is a view in end elevation of the massaging device shown in Figure 3.

Referring to the drawings in detail, 5 indicates the massaging device which comprises the handle 6 carrying at the ends

thereof the frame pieces 7 which are held together as by the rivet 8 and are formed in their lower portion to provide the spaced legs 9, these legs being connected with the side strap 10 and being joined at their centers by the adjusting screw 11. The lower ends of the legs 9 are adapted to receive the wheels 12 which may be of any suitable soft material, such, for instance, as rubber or may be made with a suitable solid center 60 provided with the rubber tires 13. The wheels are held in position on the leg members 9 through the medium of suitable bolts or rivets 14 which form an axle for the 65 wheels 12.

70 It is evident that the lower portions of the legs 9 are in yieldable relation to each other and are maintained at fixed distances apart by the adjusting screw 11. When massage of the spinal column is necessary, 75 the massaging implement is rolled up and down the back so that the wheels are on either side of the center of the spinal column and through the medium of the adjusting screw 11, the distance apart of the 80 wheels can be adjusted to fit the particular person to which the device is to be applied.

In Figure 3 I have shown a modified form 85 which consists of a handle frame piece 15, the top of which is formed in tubular fashion 16 to provide the hand grip, the opposite sides of the frame being held together through the medium of an adjusting screw 17 so that the distance apart of the legs 18 90 can be suitably adjusted. This improved one piece construction reduces the cost of the manufacture of the device and enhances the appearance thereof, and makes the device lighter and more easily handled.

95 It will be evident therefore that I have provided an improved form of massaging implement which can be used to adjust the spinal column by applying thereto a roller device which will carry on massaging operation in an efficient manner.

100 While I have illustrated and described my invention with some degree of particularity, I realize that in practice various alterations therein may be made. I therefore reserve the right and privilege of changing the form of 105 the details of construction or otherwise altering the arrangement of the correlated parts without departing from the spirit of the invention or the scope of the appended claims.

Having thus described my invention, what 110

I claim as new and desire to secure by United States Letters Patent is:—

1. A chiropractic treatment device comprising spine engaging wheels of substantial width, leg members to which said wheels are secured, straps joining said leg members, and an adjusting member connecting said straps whereby the transverse distance separating said wheels may be adjusted.
- 10 2. A chiropractic device comprising spine

engaging wheels, leg members having bowed portions, a handle to which said leg members are secured at their upper ends, side straps joining said legs, and an adjusting screw connecting said straps whereby transverse 15 adjustment of said rollers may be made.

In testimony whereof I affix my signature.

TANOUS H. DAVID. [L. S.]
